UNITED STATES PATENT OFFICE.

HENRY C. McILWAIN, OF NULL'S MILLS, INDIANA.

CLOTHES-WASHER.

SPECIFICATION forming part of Letters Patent No. 284,459, dated September 4, 1883.

Application filed March 15, 1883. (Model.)

To all whom it may concern:

Be it known that I, HENRY CLAY McILWAIN, of Null's Mills, in the county of Fayette and State of Indiana, have invented certain new and useful Improvement in Clothes-Washers, of which the following is a full, clear, and exact description.

Reference is to be had to the accompanying drawings, forming part of this specification, in which similar letters of reference indicate corresponding parts in all the figures.

Figure 1 is a sectional elevation of my improvement. Fig. 2 is a sectional elevation of the same turned one-quarter around, taken through the line *x x*, Fig. 1. Fig. 3 is a bottom view of the same. Fig. 4 is a side elevation of the lower part of the center plate, the band being shown in section. Fig. 5 is a sectional plan view of the same, taken through the line *y y*, Fig. 4.

The object of this invention is to provide clothes-washers simple and inexpensive in construction, easily operated, and rapid and effective in action.

The invention consists in a clothes-washer constructed with a tapered chamber having downwardly-inclined flanges around its lower and upper parts, and small openings through its walls beneath the said flanges, whereby the air may escape, and currents of water will be caused by the movements of the said washer to pass through and be projected against the clothes. Within the tapered chamber is secured a central plate, which has a band secured in a slot in its lower part, to receive the split lower end of the handle and connect it with the washer, as will be hereinafter fully described.

A represents a circular chamber, which is tapered upward. To the wall of the chamber *A*, at a little distance from the bottom and top of the said chamber, are attached downwardly inclined or flaring flanges *B C*. In the wall of the chamber *A*, beneath the upper parts of the flanges *B C*, are formed small openings *D E*, to let the air escape. In an opening in the top of the chamber *A* is secured a collar, *F*, through which the handle *G* passes. The handle *G* is slotted longitudinally from its lower end to receive the central plate, *H*, which divides the chamber *A* into two equal parts, and the edges of which are soldered or otherwise secured to the wall

of the said chamber. In the lower middle part of the plate *H* is formed a slot in which is secured a band, *I*, of such a size as to receive and serve as a socket for the lower end of the handle *G*.

With this construction, when the washer is forced downward upon the clothes in a tub or other suitable vessel, the air within the chamber *A* has a free escape through the holes or openings *E*, and is followed by the water, which is forced up through the clothes at the open bottoms of the said chambers by the weight or pressure of the water on the outside, and through the openings *D* from the space beneath the flange *B*. The upward taper of the chamber *A* compresses the water that is forced into it and causes the water to escape with force through the openings *E*. As the streams of water escape through the openings *E*, they strike the flange *C*, and are deflected downward, so as to strike the clothes surrounding the base of the washer. As the washer is raised, the water within the said chamber *A* is forced out by its own weight, and as the water that is in the space beneath the lower flange, *B*, cannot escape through the openings *D* into the cylinder as rapidly as the air escapes, the clothes will be caused to adhere to the flange by suction, so that the clothes will be raised to the surface at every upward movement of the washer, and quickly and thoroughly cleaned by the currents of water caused to pass through and against the clothes by the movements of the washer.

Having thus described my invention, I claim as new and desire to secure by Letters Patent—

1. In a clothes-washer, the tapering chamber *A*, provided with the downwardly-inclined flanges *B C* at its lower and upper parts, respectively, and with the openings *D E* beneath the upper parts of the said flanges, substantially as herein shown and described.

2. In a clothes-washer, the tapering chamber *A*, provided with the downwardly-inclined flanges *B C*, and the openings *D E* of the central plate, *H*, secured within the said chamber, and having the band *I* at its lower end, and the slotted handle *G*, substantially as herein shown and described.

HENRY C. McILWAIN.
